UNITED STATES PATENT OFFICE

2,564,479

FORCED CIRCULATION MULTIPLE UNIT AIR HEATING FURNACE

George B. Herbster, Cleveland, Ohio, assignor, by
mesne assignments, to 8600 Denison Company,
Cleveland, Ohio, a corporation of Ohio

Application January 7, 1948, Serial No. 827

8 Claims. (Cl. 126—110)

1

This invention relates to a heater and is an improvement on the heater disclosed and claimed in my co-pending applications Ser. No. 663,506, filed April 19, 1946, which application is now abandoned, and Ser. No. 787,455, filed November 21, 1947.

In the first of said applications, there is described a heat exchanger comprising a plurality of annular heads arranged in a row in spaced face to face relation from each other to define an axial central passage and to define between the heads radial passages connected at their inner ends with the central passage and open at their outer ends throughout the greater portion of their extent. A rotary impeller of a centrifugal radial discharge blower is arranged in the central passage and receives air from both ends and discharges it radially of the heads through the radial passages into an enclosing casing. In that structure, there is a tendency for the air discharged from the heads to swirl about the axis of the central passage in the radial passages and in the interior of the casing with the consequent loss of efficiency in the volume of air discharged from the casing into the space to be heated.

In my co-pending application, Ser. No. 787,455, the casing is modified from that of the earlier application to provide a spirally expanding peripheral wall which expands gradually in the direction of rotation of the rotor. This improvement increases the air delivery effectively but due to the limited diameter of the rotor, requires that the rotor be driven at relatively high speed.

In the present application, the flow of air through the radial passages between the heads and its discharge from the casing are greatly improved while at the same time a much lower rotor speed is required.

The principal object of the present invention is to provide a heater having an efficient heat exchanger and rotary centrifugal radial discharge air impeller so combined therewith as to provide for an efficient and better balanced flow of air in a large volume in heat exchange relation to the heat exchanger and from the heat exchanger into the space to be heated.

Other objects and advantages will become apparent from the following description wherein reference is made to the drawings in which:

Fig. 1 is a side elevation of a heater embodying the principles of the present invention;

Fig. 2 is a horizontal sectional view of the heater taken on the line 2—2 in Fig. 1;

Fig. 3 is a vertical section view of the heater taken on line 3—3 of Fig. 1.

2

Referring to Figs. 1, 2, and 3 the heater comprises a heat exchanger which is preferably formed of a plurality of annular heat exchange heads 1 arranged in a row in axial alignment in spaced face to face relation to each other so as to define central passage 2 and radial passages 3 which connect at their inner ends with the passage 2 and are open at their outer ends.

As more fully described in my above identified co-pending applications, each of the heads 1 has a combustion chamber portion 4 and stack portion 5, the former of which is open at its lower end into a burner compartment 6. A gas burner 7 is arranged in the compartment 6 and has a plurality of head portions which discharge into the combustion chamber portions 4, respectively, of the heads 1. Oil burners likewise may be used. Thus, each head, including its combustion chamber portion 4 and stack portion 5 is spaced flatwise of the heads from the heads adjacent thereto over the entire extent of its side walls so that, except for a slight blocking by the burner compartment top wall and by the accumulating head for the stack portions, the radial passages formed between the heads are open fully to the atmosphere at the outer peripheries of the heads for their entire peripheral extent.

The heater heads 1 are enclosed in a suitable casing 8 which preferably has a spiral peripheral wall 9 and outlet 10 such as described in my co-pending application Ser. No. 787,455. The casing 8 has end walls 11 which are spaced axially from the outermost heads 1 of the row of heads and have central openings 12 co-axial with the central passage 2 but of less diameter than the passage 2.

Mounted on the side walls of the casing are suitable brackets 13 which support a rotatable shaft 14 driven by means of a pulley 15, belt 16, and motor 17. Mounted on the shaft 14 between adjacent heads 1 and between the end heads of the row and the adjacent side walls 11 are sections of a rotary, centrifugal radial discharge blower impeller. Since each of the impeller sections is the same in form and function, one only will be described in detail.

As illustrated in Fig. 2, the impeller section at the extreme right comprises a hub 18 mounted on the shaft 14 for rotation therewith and a suitable spider 19 to the outer ends of which are connected a plurality of impeller blades 20. The impeller blades preferably are arranged generally parallel to the axis of the shaft 14 and are spaced apart circumferentially in the usual manner so that upon rotation, air is drawn in axially of the impeller and discharged centrifugally radially

ally therefrom. The impellers between adjacent heads are similar to the impeller described except that they are slightly shorter and all impellers are preferably of the same diameter. The extra length of the impellers between the walls 11 and the end heads of the row is provided due to the fact that they must initiate any inward flow of air.

Usually when such impellers operate to draw in air from an adjacent air mass which is relatively static, the first inch or so axially from the inlet is not as effective for drawing in and discharging air as is the remainder of the length of the blades because the air is already in motion axially of the impeller as to said remainder of the length of the blades. Consequently, the blades 20 inwardly, axially of the impeller from the ends of the impeller may be shorter than those blades which are at the ends of the impeller as generally the air is already in motion axially of the impeller when it reaches the planes of the radial passages between the heads.

It will be noted from Fig. 2 that the impeller blades are closely confined between the heads and between the side walls and adjacent heads so as to prevent a return of air toward the axis of the impeller sections around the ends of each impeller section. Furthermore, the impeller blades are spaced outwardly beyond the major portion of the radial length of the heating heads so that the air drawn in by the impeller sections is caused to pass into heat exchange relation to the heads before it reaches the blades except for the radially outermost extremities of the heads. Due to the much larger diameter of the impeller relative to the heads in the present form of the invention, as compared to the form shown in my co-pending applications, the impeller may be rotated at considerably slower angular speeds for the same volume of air, thus reducing vibration and also reducing eddy-currents between the heads. In fact, the volume of air delivered is very greatly increased over that obtainable with equal size heat exchange heads using an impeller of the diameter of the central passage 2. Thus a better balance between heat exchange surface, volume of air and time of exposure of the air to the surface is obtained.

The impeller sections provide an impeller means between the axis and blades of which the major portion of the heat exchange means is disposed. The structure above described is particularly suitable for space heaters and central furnaces.

Having thus described my invention, I claim:

1. A heat exchanger and blower combination comprising a plurality of upright substantially annular disc-like hollow heat exchange heads arranged in a row in axial alignment and spaced face to face relation and defining a central axial passage with generally annular radial passages between adjacent faces of the heads and connected to and radiating from the central passage, each of said heads having a combustion chamber portion at its lower portion and an exhaust portion at its upper portion, said combustion chamber and exhaust portions of each head being spaced apart endwise of the row from the corresponding portions of adjacent heads and each head having at least one passage extending clockwise, and at least one passage extending counterclockwise about the central passage from the combustion chamber portion to the exhaust portion, rotary blower impeller sections coaxial with the central passage and extending radially

outwardly from the central passage into said radial passages, respectively, and arranged to receive air axially, and means supporting said sections for rotation about the axis of the central passage.

5 2. A combination according to claim 1 characterized in that each of said sections has a plurality of impeller vanes spaced radially outwardly from its axis of rotation nearly to the outer peripheral limits of the heat exchange heads.

10 3. A combination according to claim 1 characterized in that said heads have annular wall surface portions disposed close to the ends of the sections for constraining air passing between adjacent heads to pass between the end limits of the impeller section which is between the heads.

15 4. A heat exchanger and blower combination comprising a plurality of upright generally annular disc-like hollow heat exchange heads arranged in a row in axial alignment and in face to face spaced relation and defining a central passage and defining between adjacent heads radial passages which are connected at their inner ends to the central passage, each of said heads

20 having a combustion chamber portion at its lower portion and an exhaust portion at its upper portion, said combustion chamber and exhaust portions of each head being spaced apart endwise of the row from the corresponding portions of adjacent heads and each head having at least one passage extending clockwise, and at least one passage extending counterclockwise about the central passage from the combustion chamber portion to the exhaust portion, a casing enclosing the heads and having a front wall and rear wall spaced from the ends of the row of heads, respectively, said walls having air inlet passages aligned with the central passage, centrifugal blower impeller sections in the radial passages, 25 and between the end heads of the row and said walls, respectively, said sections being coaxial with the central passage and having their outer peripheries radially outwardly beyond the inner periphery of the heads, means supporting the impeller sections for rotation about the axis of the central passage, and said casing having a discharge opening spaced from the inlet openings.

30 5. A heater comprising a plurality of upright, substantially annular disc-like hollow heating heads arranged in a row in axial alignment and flatwise spaced relation to each other and providing a central axial passage and generally annular radial passages between adjacent heads and leading from the central passage and open

35 at their outer limits, each of said heads having a combustion chamber portion at its lower portion and an exhaust portion at its upper portion, the said combustion chamber and exhaust portions of each head being spaced apart endwise of the row from the corresponding portions of adjacent heads, each head having a plurality of

40 passages therein extending circumferentially of the heads in opposite directions from its combustion chamber portion to its exhaust portion, burner means to supply combustible media into the combustion chamber portions, rotary impeller means coaxial with the central passage and including circumferentially extending rows of impeller blade portions in alignment radially with

45 the radial passages, said rows of blade portions being coaxial with the row of heads and disposed radially outwardly from the axis at least beyond the inner periphery of the heads.

50 6. A heater according to claim 5 characterized in that the blade portions are between the heads.

7. A heater according to claim 5 characterized in that said impeller means includes a rotatable shaft coaxial with and extending into the central passage and supporting means for the blade portions carried by the shaft and extending radially outwardly through the radial passages.

8. A heater according to claim 5 characterized in that said heads are imperforate between their inner and outer radial limits.
